UNITED STATES PATENT OFFICE.

WILLIAM THOMAS, OF BEATRICE, NEBRASKA, ASSIGNOR TO DEMPSTER MILL MANUFACTURING COMPANY, OF BEATRICE, NEBRASKA, A CORPORATION OF NEBRASKA.

APPARATUS FOR OPERATING PUMPS.

1,329,560.

Specification of Letters Patent.

Patented Feb. 3, 1920.

Application filed June 6, 1916. Serial No. 102,044.

To all whom it may concern:

Be it known that I, WILLIAM THOMAS, a subject of the Emperor of Germany, residing at Beatrice, in the county of Gage and

5 State of Nebraska, have invented certain new and useful Improvements in Apparatus for Operating Pumps, of which the following is a specification.

This invention relates to certain improvements in apparatus for operating pumps; and the objects and nature of the invention will be readily understood by those skilled in the art in the light of the following explanation of the accompanying drawings

10 illustrating what I now believe to be the preferred embodiment and mechanical expression of the invention from among other forms, constructions and arrangements within the spirit and scope thereof.

15 The apparatus of my invention embodies motor, *i. e.*, power, driven mechanism for reciprocating vertical plunger well and other pumps, and my invention is characterized in whole or in part, by the provision of a 20 pump jack having its crank shaft connected by one or more upright pitmen and other connections, to the pump piston rod, said jack having a drive shaft approximately aligned with the crank or other main shaft 25 of the motor and having direct driving connection therewith through the medium of a slip coupling so constructed and arranged that the motor and jack can be readily assembled and directly coupled together without 30 requiring expensive skilled labor, and whereby the jack and motor can be easily and readily operatively disconnected and connected, without changing the position of or shifting either the jack or motor, thereby 35 avoiding the use of belt and gear driving connections between the motor and jack and the disadvantages of such transmission devices on the farm and elsewhere where such apparatus are often exposed to the weather 40 and to interference by live stock.

45 The invention consists in certain novel features in construction, and in combinations and arrangements as more fully and particularly set forth and specified herein-
after.

50 Referring to the accompanying drawings:

Figure 1, is a perspective view of apparatus embodying my invention.

55 Fig. 2, is a side elevation.

Fig. 3, is a top plan of the pump jack, the pump standard and pitmen being shown in horizontal section, the coupling to the motor shaft being shown.

Fig. 4, is a detail side elevation of the 60 main frame of the pump jack and the means for clamping the same to the pump standard.

Fig. 5, is a front elevation of the jack, the pitmen and motor shaft being broken away. 65

Figs. 6 and 7, are detail views of the slip coupling between the motor shaft and drive shaft of the jack.

In the particular embodiment illustrated, 70 I show the pump platform 3, formed by strong planks or timbers, with the vertical pump standard or barrel rising therefrom, with the vertical pump plunger actuating or piston rod 20, projecting above the pump barrel.

75 The pump jack comprises a strong rigid main frame 1, inclining downwardly and laterally from the pump barrel and at its upper end formed with a rigid jaw, usually a V-jaw 1^a, to fit the pump barrel and adapted to be rigidly clamped thereto by an opposite or movable jaw or cross head 15, and connecting bolts and nuts 1^b.

80 The upper end of this frame, just in rear of the jaw 1^a, is formed with an elongated transverse bearing 1^c, receiving the crank shaft 9, of the jack. The projecting ends of 85 this shaft receive the large crank gears 5. Each gear 5, is formed with a radial series of perforations 5^a, any one of which is 90 formed to receive a wrist or crank pin 17. These perforations permit adjustment of 95 the crank pins to vary the stroke of the pump actuating rod, as will be readily understood by those skilled in the art.

95 These crank pins are mounted in the lower ends of the upright pitman 18, which are connected at their upper ends by cross head 19, and this cross head is loosely and operatively coupled in any suitable manner 100 to the rod 20, as will be understood by those skilled in the art. However, I do not wish to limit my invention to any particular manner of or means for operatively coupling the pitman or pitmen to the pump 105 rod 20, nor to the double geared arrangement, as a single gear 5 can be utilized for driving the shaft 9, as those skilled in the art will understand.

110 The outer end of the main frame is forked

2
or bifurcated and formed with a transverse bearing 1^a, receiving the intermediate shaft 10, at its projecting ends provided with pinions 6, meshing with and driving the large 5. crank gears 5.

At its central portion, the shaft 10, is provided with gear 7, located in the bifurcation of the frame. This gear 7, meshes with and is driven by the pinion 8, to drive the intermediate shaft and the crank shaft 9. The pinion 8, is located on the center of the jack drive shaft 11. The shaft 11, is mounted in a pair of open journal boxes 16, having attached top caps. The pinion 8, is located between these boxes. The lower halves of the boxes are formed in the upper ends of a pair of spaced parallel upwardly and forwardly inclined arms 1^b, from the front end of the main frame and integral therewith, 20 and forming part of the bifurcated front end of said frame. Both ends of the shaft 11, are extended laterally beyond the vertical planes of the large gears 5, so that either end of the shaft can be directly coupled to 25 the motor shaft as hereinafter explained. The front end of the frame is formed with a pair of vertical arms or legs 1^c depending from the front ends of the fork formed by the bifurcation and having flat vertical 30 front faces and elongated vertical slots.

An upright supporting standard 2, is provided for the front end of the main frame. This standard has a bottom foot or base resting on and bolted or otherwise secured 35 to the pump platform 3. The upper portion of this standard is centrally and vertically slotted to receive the gear 7 while the rear faces of the two uprights thus formed are flat and vertical to receive the depending 40 arms or legs 1^c and said uprights are formed with vertical slots 2^a to register with the slots in the legs 1^c. The legs 1^c and the standard 2 are rigidly clamped together by bolts 2^b passing through said slots. The 45 main frame and parts carried thereby can be adjusted vertically to approximately aline the operating shaft 11 with the main shaft of the motor, by loosening the bolts 1^b and 2^b so that the clamp 1^a, 15, can slide 50 vertically on the pump standard 4 and so that the depending legs 1^c can slide vertically on the front supporting standard 2. When the jack has been adjusted to the desired elevation, the bolts 1^b and 2^b are tightened 55 to rigidly lock the main frame to the pump standard 4 and to the front supporting standard, and thereby fixedly support and hold the jack in the desired position.

In the drawings, I somewhat diagrammatically illustrate any suitable motor or engine M for driving the pumping jack. I usually employ a liquid hydrocarbon, such as a gasoline, engine for this purpose. The motor is provided with a crank, engine, or 65 other main drive shaft 14, usually at both

ends projecting beyond the fly wheels and power transmission pulley or pulleys commonly mounted thereon.

This motor is usually located on the pump platform 3 and is arranged beside the pumping jack with the motor shaft 14 approximately alined with the drive shaft 11 of the jack. As before described, the main frame of the jack is adjusted vertically to bring the shaft 11 to the horizontal plane of the 75 motor shaft 14.

The motor can be arranged on either side of the pumping jack to bring either projecting end of the motor shaft into more or less close proximity with either projecting end 80 of the shaft 11, of the pumping jack. These two adjacent approximately alined shaft ends are united to rotate together yet so as to permit longitudinal operative disconnection, by a slip coupling consisting of a 85 spigot member normally fixed on one shaft end, and a bell member normally fixed on the other shaft end, with the bell and spigot telescoping or interlocking between the shaft extremities. In the embodiment illustrated, 90 the spigot (male) member is secured on the projecting end of the motor shaft 14 and consists of a strong casting or block forming a socket portion 13 having a longitudinal bore or socket of a size to more or less 95 snugly receive said shaft end and a radial set or clamping screw 13^a for rigidly clamping said member to said shaft, and also forming a reduced spigot portion 13^b in outward longitudinal continuation of the socket portion beyond the shaft end, and forming a vertical annular shoulder 13^c at the outer end of the socket portion and around the inner end of the spigot portion. The spigot portion is other than circular in cross section, for instance, I show the same approximately rectangular in cross section so as to provide several similar angularly arranged flat faces. The shaft end receiving socket 100 preferably extends throughout only a portion of the length of the socket member. 105

The bell member consists of a strong comparatively heavy sleeve-like block or casting forming a sleeve or collar 12 longitudinally receiving the end of the pumping jack shaft 11 and adapted to be normally clamped rigidly thereto by set screw 12^a or the like. This bell member also forms the enlarged bell 12^b in longitudinal outward continuation of the sleeve portion 12. The bore or 120 socket of this bell is enlarged with respect to the bore of sleeve portion 12 which opens thereinto so that the inner end wall or bottom of the bell is formed by a vertical annular shoulder 12^c surrounding the inner end 125 of the bore of the sleeve portion.

The bore or socket of the bell is open at its outer end, and the bell projects from the extremity of shaft 11 a distance approximately equal to the longitudinal length of the spigot 130

13^a which is approximately equal to the distance between the shaft ends. The bore or socket of the bell is formed to longitudinally receive the spigot and to more or less snugly fit the same, and the cross sectional formation of the bore or socket of the bell approximately conforms to the cross sectional formation of the spigot to provide abutting faces between the bell and spigot requiring the two parts to rotate together although permitting longitudinal separation of said parts. The angularly-arranged spigot-abutting faces 12^a of the bell bore are each arched or rounded longitudinally of said bore with the crown of the arch approximately midway the length of the face, thereby forming the bore longitudinally flaring or enlarging in opposite directions from the center of its length toward its opposite ends. At approximately the center of its length, the walls of the bell bore hence more or less snugly receive the spigot at approximately the center of its length, and thus provide opportunity for the two coupling members to rock on each other during rotation without binding, in the event that the shafts 11, 14 or the coupling members, are somewhat out of alignment. This is a feature of material advantage inasmuch as it is sometimes exceedingly difficult to arrange the motor shaft and the jack drive shaft in exact alignment, or to determine whether these parts are more or less accurately aligned. By this peculiar slip coupling device, the motor shaft 35 can drive the drive shaft of the jack without loss of power and without binding, even though the parts have not been accurately set up and assembled.

In assembling the parts, the bell member 40 is slipped on the end of shaft 11 and moved back thereon with the shaft end extending into the bell. The spigot end is located in proper operative position on the motor shaft end and fixed by tightening the set screw 13^c. The motor is then placed in final position 45 beside the pumping jack with the shafts 11, 14 approximately aligned, and with their adjacent ends spaced the necessary distance apart, *i. e.*, with the outer usually somewhat rounded end face of the spigot 13^b approximately engaging the end face of the shaft 11. The bell member is then slipped outwardly on shaft 11 until the bell bore or socket approximately entirely incloses the 55 spigot with the outer end edge of the bell spiced slightly from the shoulder 13^c of the spigot member. The set screw 12^a is then tightened to fixedly secure the bell to its shaft.

50 The two shafts are thus operatively united to rotate together, and the motor can be started and the motor shaft will actuate the shaft 11 through the medium of the slip coupling.

55 If for any reason, it should be desired to

sever the operative connection between the motor shaft and jack drive shaft, it is only necessary to loosen the set screw 12^a and then move the bell member longitudinally of the shaft 11 in a direction away from the motor, 70 until the spigot is entirely uncovered or released from the bell. The motor can then be operated independently of the pumping jack.

The motor can again be coupled to the pumping jack for driving the same, by slipping the bell member on shaft 11 until it is operatively interlocked with the spigot, and then securing the bell in operative position by tightening the set screw 12^a.

It will be noted that the slip coupling will 80 not interfere with the location of a belt pulley on either end of the motor shaft, and use of said pulley in driving a belt, even when the motor is coupled to and driving the pumping jack.

85 It is evident that various changes, modifications, variations and departures might be resorted to without departing from the spirit and scope of my invention and hence I do not wish to limit the invention to the exact 90 disclosures hereof.

What I claim is:—

1. In pump operating apparatus, in combination, a pumping jack having its drive shaft provided with a slip coupling member 95 on and projecting from one end thereof, means whereby said shaft is rendered vertically adjustable, a motor having its shaft approximately aligned with said drive shaft and provided with a slip coupling member 100 on and projecting from one end and interlocked with said first mentioned member to operatively connect the motor shaft in driving relation with the jack shaft.

2. In pump operating apparatus, in combination, a pumping jack having its drive shaft provided with a slip coupling member 105 on and projecting from one end thereof, a motor having its shaft approximately aligned with said drive shaft and provided with a 110 slip coupling member on and projecting from one end and interlocked with said first mentioned member to operatively connect the motor shaft in driving relation with the jack shaft, said members being longitudinally separable, said drive shaft being vertically adjustable with respect to said motor shaft.

3. In pump operating apparatus, in combination, a motor having a horizontal main 120 shaft, a pumping jack having a horizontal actuating shaft, said jack provided with means for adjusting the jack vertically to bring its actuating shaft into approximate alignment with said main shaft, and a universal separable rotary coupling connection 125 bridging the distance between the adjacent ends of said shafts establishing operative driving connection from the motor shaft to the jack shaft.

4. In pump operating apparatus, in combination, a pumping jack embodying a vertically-adjustable actuating shaft and a supporting frame, a motor separate and distinct from said jack and its supporting frame and embodying a main shaft approximately alined with said actuating shaft and removably coupled thereto for driving the same, substantially as described.
5. In pump operating apparatus, a pumping jack comprising a main frame provided with means at one end for clamping the same to the pump standard, a supporting standard for the opposite end of said frame, a jack actuating shaft mounted in said frame, means whereby said frame is adjustable to vary the vertical position of said shaft, a pitman, eccentric pitman actuating means carried by said frame, driving connections between said shaft and said means, a motor adapted to be arranged with its motor shaft approximately alined with said actuating shaft, and means directly coupling said motor shaft to and in driving relation with said actuating shaft.
6. In combination, a main frame provided with means for rigidly clamping it to a pump standard, an upright supporting standard for said frame, an adjustable clamping connection between said standard and the frame, whereby the frame can be adjusted vertically with respect to the standard, a jack actuating shaft mounted in the frame, an independent motor having a motor shaft, detachable coupling connections adapted to establish driving connection from the motor shaft to said actuating shaft, said frame adjustment adapted to bring the actuating shaft into approximate alinement vertically with said motor shaft, and pitman actuating gearing and shafts mounted in the frame and driven by said actuating shaft.
7. In pump operating apparatus, a pumping jack having a horizontal rotary actuating shaft and embodying means for rigidly securing the jack to a pump and means for varying the vertical position of said shaft to bring the same into approximate longitudinal alinement with the horizontal motor shaft of an independently mounted portable motor removably arranged adjacent to said jack, and detachable universal coupling connections adapted to operatively connect adjacent ends of said shafts for rotatively driving the actuating shaft from the motor shaft.
8. A pumping jack comprising a frame at one end provided with a clamp for securing the same to a pump in vertical adjustment with respect to the pump, an upright standard, means normally clamping said standard against the outer end of said frame and whereby said frame is vertically adjustable with respect to said standard, and gearing carried by said frame and including a trans-
- verse rotary actuating shaft adapted to be detachably coupled to and driven by the motor shaft of an independent portable motor removably arranged adjacent to the jack, said frame being adjustable vertically to bring said actuating shaft into approximate vertical alinement with said motor shaft.
9. A pumping jack comprising a frame at one end having means for securing the same to a pump or other support, a vertical standard at its lower end adapted to be fixed to a support, means securing the opposite end of the frame to said standard in vertical adjustment, a transverse actuating shaft mounted in the frame above said standard and having a projecting end for the attachment of driving means; a transverse shaft mounted in the opposite end of the frame and having a crank for connection with the pump, and an intermediate transverse shaft mounted in the frame and geared to said two first mentioned shafts.
10. In pump operating apparatus, a pumping jack comprising a frame, pump rod actuating means mounted in said frame and including a rotary actuating shaft, means for securing said frame to a pump or other support, an upright standard depending from said frame and at its lower end adapted to rest on and be secured to the floor or other base, and clamping means by which said frame is normally fixed to said standard, said clamping means including a transverse clamping bolt, said frame or standard being vertically slotted to receive said bolt and permit vertical adjustment of the frame on the standard when said clamping means is loosened.
11. In pump operating apparatus, a pumping jack comprising a frame, pump rod actuating means mounted in said frame and including an actuating shaft adapted to be brought into approximate longitudinal alinement vertically with the horizontal shaft of a motor, said frame provided with means for clamping the same to a pump or other support, a frame supporting standard depending therefrom and resting on the floor or other base, said frame being vertically adjustable on said standard, said frame and standards having parallel vertical portions, and clamping means normally clamping said portions together and holding the frame to the standard.
12. In pump operating apparatus, a pumping jack comprising a frame, pump rod actuating means mounted in said frame and including an actuating shaft adapted to be brought into approximate longitudinal alinement vertically with the horizontal shaft of a motor, said frame provided with means for clamping the same to a pump or other support, a frame supporting standard depending therefrom and resting on the floor

or other base, said frame being vertically adjustable on said standard, said frame having a vertically disposed and elongated end arranged beside and slidable vertically on 5 said standard, and means normally rigidly clamping said frame end against said standard.

13. In pump operating apparatus, a pumping jack comprising a frame at one end provided with a clamp for securing the same to a pump or other support and at the opposite end having a vertically elongated portion, a frame supporting standard extending up beside and fitting said portion and depending

therefrom to rest on the floor or other base, 15 means normally rigidly clamping said frame to the standard comprising a clamping bolt extending transversely through said portion and the frame, said frame being vertically adjustable on the standard when said means 20 is loosened, and pump rod operating mechanism mounted in said frame and including a rotary actuating shaft adapted to be shifted vertically for alinement with the shaft of a motor by the vertical adjustment of said 25 frame.

WILLIAM THOMAS.
